EXPLOSIVE CONTAINER

George H. Neff, St. Louis, Mo.

Application December 2, 1939, Serial No. 307,307

1 Claim. (Cl. 102—24)

My invention consists in a new and useful improvement in explosive containers, and is designed more particularly to provide a container for non-water proof high explosives to be inserted into a bore in the ground under conditions in which the bore becomes clogged or crowded by unstable matter, such as sand, gravel or muck flowing into the bore, and also where the container is subjected to high head pressure under long columns of water. The peculiarly novel and useful feature of my improved container is the peculiar form and character of the closure plates and their application to the tubular member.

While I have illustrated in the drawings filed herewith and have hereinafter fully described one specific embodiment of my invention, it is to be distinctly understood that I do not consider my invention limited to said specific embodiment, but refer for its scope to the claim appended hereto.

In the drawings:

Fig. 1 is a side elevation of my improved container.

Fig. 2 is an enlarged fragmentary view of the outer tube of my container, certain of its layers being cut away in order to illustrate its construction.

Fig. 3 is a similar view of the inner tube of my container.

Fig. 4 is a horizontal section on the line 4—4 of Fig. 1.

Fig. 5 is a vertical section on the line 5—5 of Fig. 1.

Fig. 6 is a vertical section on the line 6—6 of Fig. 1.

My improved container consists of the body portion formed by the outer tube A and the inner tube B, and the two end closures C and D. I produce the outer tube A by rolling a continuous web 1 of fiber board coated with a suitable adhesive 2, to form a roll of suitable diameter, formed of five layers of fiber board, with the outer longitudinal seam 1—a. I produce the inner tube B by superimposing a series of spirally wound layers, two of fiber board, and two of nitro-cellulose sheets, alternated. I so arrange these layers that the innermost layer 3 is a sheet of nitro-cellulose. This layer 3 is coated with a layer of suitable adhesive 4 and a layer of fiber board 5 is superimposed. The layer 5 is coated with a layer of adhesive 6, and a layer of nitro-cellulose 7 is superimposed. The layer 7 is coated with a layer of adhesive 8 and a layer of fiber board 9 is superimposed. It is to be noted that

the meeting edges of each layer abut and do not overlap, and that these meeting edges 3—a, 5—a, 7—a and 9—a are in staggered relation.

When the inner tube B has been thus fabricated, the outer layer 9 thereof is covered with a coating of adhesive 10 and the inner tube B is introduced into the outer tube A, the layer of adhesive 10 acting to unite the tubes A and B.

The closure C comprises an orificed end plate 10 C—1 fixed on the body of the container, and a removable cap C—2 therefor. The plate C—1 comprises an annulus 11 having the inner peripheral flange 12 and the outer peripheral flange 13 having an annulus 14 with a flange 15 having an inwardly turned lip 16. The cap C—2 comprises the plate 17 and its peripheral flange 18 turned upon itself to form the outer flange 19. The plate C—1 is applied to one end of the body of the container so that the tubes A and B are closely confined between the flanges 13 and 15, their ends abutting the annulus 14. When the plate C—1 has been thus applied, the lip 16 is forced inwardly into the outer surface of the tube A, thus securely locking the plate C—1 upon the body, to form a thoroughly water proof juncture between the body and the plate C—1. After the container has been charged with the explosive, the cap C—2 is applied, the flanges 18 and 19 embracing the flange 12. It is to be understood that the plate C—1 and the cap C—2 are so designed and related that the resilient flanges 12 and 18 and 19 are caused to be in intimate contact when the cap C—2 is applied, to effect a water proof juncture between the plate C—1 and the cap C—2. Also it is to be noted that the flanges 12, 18 and 19 are so designed that the cap C—2 is received entirely within the end plate C—1, so that the annulus 14 forms an unobstructed end surface of the container.

The closure D comprises an orificed end plate D—1 fixed on the body of the container and a chamber D—2 so fixed upon the plate D—1 as to extend within the container when the plate D—1 is applied to the end of the body of the container, to serve as a receptacle for the detonator of the explosive within the container. The plate D—1 comprises an annulus 20 having an outer peripheral flange 21 having an annulus 22 with a flange 23 having an inwardly turned lip 24. The chamber D—2 is formed at one end with a pair of outer peripheral flanges 25 and 26 between which is embraced the inner edge of the annulus 20, the juncture being such that a water proof joint between the plate D—1 and chamber D—2 is effected. The plate D—1 is applied

to the end of the body of the container so that the tubes A and B are closely confined between the flanges 21 and 23, their ends abutting the annulus 22. When the plate D-1 has been thus applied, the lip 24 is forced inwardly into the outer surface of the tube A, thus securely locking the plate D-1 upon the body to form a thoroughly water proof juncture between the body and the plate D-1.

After the container has been charged and sealed as above described it receives a thorough coating 27 of a water proof material such as paraffin.

Having described my invention, what I claim is:

5 In an explosive container, the combination of a tubular body; a closure plate comprising an annulus having an inner peripheral flange and an outer peripheral flange having extending therefrom an annulus with an outer peripheral flange; and a removable cover comprising a circular disk and a peripheral flange doubled upon itself to form a second outer peripheral flange, between which the inner flange on the closure plate is received, the parts being so designed and related that when the cover is applied to the closure plate, the entire cover is recessed within the end of the container formed by the closure plate.
